UNITED STATES PATENT OFFICE

172,766

SPRINKLER HEAD UNIT

Elmer N. Reynolds, Rivera, Calif.

Application October 22, 1953, Serial No. 27,286

Term of patent 14 years

(Cl. D91—1)

To all whom it may concern:

Be it known that I, Elmer N. Reynolds, a citizen of the United States, residing at Rivera, in the county of Los Angeles and State of California, have invented a new, original, and ornamental Design for a Sprinkler Head Unit, of which the following is a specification, reference being had to the accompanying drawing, forming part thereof, and wherein:

Fig. 1 is a perspective view of a sprinkler head unit embodying my new design;

Fig. 2 is a top plan view of the sprinkler head unit;

Fig. 3 is a front elevational view thereof; and
Fig. 4 is a side elevational view thereof.

I claim:

The ornamental design for a sprinkler head unit, as shown.

No references cited.
